United States Patent Office

Des. 203,268
Patented Dec. 21, 1965

203,268

TOOL FOR OPENING BOXES

Ernest E. Swann, Jr., 2703 Whispering Pines Road,
Albany, Ga.

Filed Oct. 12, 1964, Ser. No. 82,136

Term of patent 14 years

(Cl. D22—3)

Fig. 1

Fig. 2

Fig. 4

Fig. 5

Fig. 3

Fig. 6

Fig. 7

FIGURE 1 is a top plan view of a tool for opening boxes, embodying my new design.

FIGURE 2 is a bottom plan view thereof.

FIGURE 3 is an end elevational view thereof taken from the left end of FIGURE 1.

FIGURE 4 is a side elevational view taken from the left side of FIGURE 3.

FIGURE 5 is a side elevational view taken from the right side of FIGURE 3.

FIGURE 6 is a vertical sectional view taken along the line 6—6 of FIGURE 4.

FIGURE 7 is a perspective view thereof.

I claim:

The ornamental design for a tool for opening boxes, as shown.
